UNITED STATES PATENT OFFICE.

JOHN F. WERLE, OF BROOKLYN, NEW YORK, ASSIGNOR TO HOOLE MACHINE & ENGRAVING WORKS, INCORPORATED, OF BROOKLYN, NEW YORK, A CORPORATION OF NEW YORK.

PRINTING-MACHINE.

1,273,295.

Specification of Letters Patent.

Patented July 23, 1918.

Application filed April 2, 1918. Serial No. 226,164.

To all whom it may concern:

Be it known that I, JOHN F. WERLE, a citizen of the United States, residing in the borough of Brooklyn of the city of New York, in the State of New York, have invented certain new and useful Improvements in Printing-Machines, of which the following is a specification, reference being had to the accompanying drawings, forming a part hereof.

Statements to customers of banks and other financial institutions, pages of loose-leaf ledgers, and other stationery of the same general class, of which only a limited number of copies, perhaps only one or two, are supplied for each individual customer, bear the names and sometimes the addresses of the individual customers. To write in the name or the name and address, on each sheet, either by hand or with a typewriting machine, requires too much time and labor. The use of machines of the addressograph character is sometimes resorted to, but the impressions yielded are often blurred or indistinct and are generally not pleasing in appearance. The object of this invention is to produce a printing machine with which names or names and addresses can be printed on such stationery so as to yield clear impressions and with great speed and economy of labor. In accordance with the invention a printing machine of the plunger type is provided with a carrier capable of receiving a number of linotype slugs, which carrier can be advanced automatically at each operation to bring a new slug to the line of printing, or can be made to repeat as often as desired by the operator, and can be replaced quickly by any similar carrier, so that a great number of impressions, limited even to a single impression of each name, can be struck off rapidly, with a perfect impression in each case. The invention will be more fully explained hereinafter with reference to the accompanying drawings in which it is illustrated and in which—

Figure 1 is a view in elevation of the upper part of a printing machine which embodies the invention.

Fig. 2 is a view of the same in front elevation.

Fig. 3 is a detail view, on a larger scale, of the carrier and some of its associated parts.

Fig. 4 is a view of the same as seen from the right hand in Fig. 3.

Fig. 5 is a view partly in horizontal section on the plane indicated by the broken line 5—5 of Fig. 4, looking in the direction of the arrows, one of the slugs being shown as withdrawn from the carrier.

In the machine illustrated in the drawings, a suitable standard *a* supports a platen *b*, an ink plate *c*, a driven shaft *d* with its crank disk *d'*, a vertically moving plunger *e* and inking mechanism *f*. All of these parts may be constructed and arranged to operate as usual.

The plunger *e* carries a frame *g* which has secured thereto, at its lower end, a carrier *h*, the frame and carrier preferably having a dovetail joint, as at *h'*, and being held together, as by a screw *h*² and a clip *h*³, so that the carrier can be detached readily from the frame if desired.

The L-shaped carrier *h* supports a spindle *i* on which is mounted rotatably a sleeve *k*, which may be formed or provided, at one end, with a ratchet feed wheel *k'* and a toothed stop wheel *k*², the sleeve being shown as having the stop wheel *k*² formed therewith, while the feed wheel *k'* is secured thereto by screws *k*³. The spindle *i* is provided at its free end with a washer *i'* and bolt *i*² by which the sleeve *k* can be secured detachably on the spindle *i*; the washer *i'* having a diameter less than the external diameter of the sleeve *k*.

On the sleeve *k* is mounted detachably, but not rotatably, a carrier drum *l*, which is slotted radially, as at *l'*, to receive a number of linotype slugs, indicated at *m*. The carrier drum is notched, as at *l*², to engage a pin *l*⁴ secured in the sleeve *k*, so as to prevent rotation of the carrier drum *l* with respect to the sleeve *k*. At its end adjacent to the shoulder *k*⁵ of the sleeve, the carrier drum *l* may have secured thereto an annular

- plate l^3 to form a stop for the slugs m . At its other end the carrier drum l has secured to it an annular plate n . Between the end of the carrier drum and the plate n is interposed a friction ring n' provided with spring fingers n^2 adapted to bear frictionally against the end of the corresponding slug m to hold it in place in its slot. The screws n^3 , by which the ring n is secured 5 to the carrier drum, are arranged to alternate with the slots of the drum and the spring fingers, as shown, so that, the ring n' being somewhat elastic, any screw can be set up more or less so as to regulate the pressure of the adjacent spring fingers. The carrier drum, with its slugs, is held in place on the sleeve h by a lock o pivoted at o' on the carrier h and provided with a pin o^2 for convenient manipulation.
- 10 A spring-pressed detent p , pivoted on the carrier h , engages the stop wheel k^2 so as to prevent accidental movement thereof and insure accurate positioning of each slug as it is brought to the line of printing.
- 15 20 A driving pawl q is pivoted on the head a' of the standard a and is held by a spring q' in driving relation with the feed wheel k' . This pawl is also provided with a pivoted handle q^2 , notched, as at q^3 , for engagement 25 with a fixed pin q^4 , so that the pawl q can be held out of driving relation with the feed wheel k' or permit it to stand in driving relation therewith, at the will of the operator.
- 30 35 In the use of the machine the linotype slugs are inserted in the slots of the carrier drum and the drum is then slipped upon the sleeve h and held in place thereon by the latch o . The machine being then set in motion, with the pawl q in operative relation 40 with the feed wheel k' , the carrier drum is advanced one step at each reciprocation of the plunger, the feed wheel k' being brought into engagement with the pawl q , as the 45 plunger approaches the upper limit of its stroke. The drum is held in this position by the hold pawl p and, the type having been inked in the usual manner, an impression is made upon the sheet placed on the platen to 50 receive it. With the driving pawl q in working relation with the ratchet wheel k' , a new slug is brought to the printing line at every operation and each sheet placed on the platen receives therefore a single impression.
- 55 60 55 When all of the slugs on the drum have been used, another drum, previously loaded, can be substituted quickly for the drum used. In this manner a great number of single impressions can be struck with great rapidity. 60 In some cases it may be desired to make more than one impression from the same slug and in such cases the pawl q is held out of working relation with the ratchet wheel k' by means of the notched lever q^2 , until the

number of impressions desired by the operator has been struck. 65

It will be understood that various changes in details of construction and arrangement may be made to suit different conditions of use and that the invention, except as pointed out in the accompanying claims, is not limited to the precise construction shown and described herein. 70

I claim as my invention:

1. In a printing machine, the combination 75 of a reciprocating carrier having a spindle, a sleeve mounted rotatably on the spindle, a carrier drum mounted to rotate with the sleeve and detachable therefrom and provided with a plurality of radial slots to receive printing slugs, means to retain the sleeve on the spindle, means to retain the carrier drum detachably on the sleeve, and means to rotate the sleeve. 80

2. In a printing machine, the combination 85 of a reciprocating carrier having a spindle, a sleeve mounted rotatably on the spindle and provided with a driving ratchet wheel, a carrier drum mounted on the sleeve to rotate therewith and provided with a plurality 90 of radial slots to receive printing slugs, means to retain the carrier drum in position on the sleeve, and a driving pawl mounted on a fixed part of the machine in working relation with the ratchet wheel. 95

3. A carrier drum for a printing machine having a plurality of radial slots to receive printing slugs, an end plate against which the slugs may abut at one end, an annular 100 plate secured to the drum at the other end and a slotted friction ring interposed between the last named plate and the carrier drum and having radial fingers adapted to bear against the ends of the slugs.

4. A carrier drum for a printing machine 105 having a plurality of radial slots to receive printing slugs, an end plate against which the slugs may abut at one end, an annular plate secured to the drum at the other end, a slotted friction ring interposed between the 110 last named plate and the carrier drum and having radial fingers adapted to bear against the ends of the slugs, and screws adapted to draw one part or another of said annular plate more closely toward the drum to cause 115 the radial spring fingers to bear more tightly against the ends of the slug.

5. In a printing machine, the combination 120 of a reciprocating carrier having a spindle, a shouldered sleeve, means to retain the sleeve detachably on the spindle, a driving ratchet wheel for the sleeve, a carrier drum provided with a plurality of radial slots to receive printing slugs, means to retain the carrier drum detachably on said sleeve and a pawl mounted on a fixed part of the machine in operative relation with said ratchet wheel. 125

6. In a printing machine, the combination of a reciprocating carrier having a spindle, a shouldered sleeve mounted rotatably on the spindle, a feeding ratchet wheel and a stop wheel mounted to rotate with the sleeve, a 5 carrier drum provided with a plurality of radial slots to receive printing slugs, means to retain the carrier drum detachably on the

sleeve, a hold pawl mounted on the reciprocating carrier for coöperation with the stop 10 wheel and a driving pawl mounted on a fixed part of the machine for coöperation with the driving ratchet wheel.

This specification signed this 30th day of March 1918.

JOHN F. WERLE.
